UNITED STATES PATENT OFFICE

LADISLAS TURCHANYI, OF SASHALOM, NEAR BUDAPEST, HUNGARY, ASSIGNOR TO MAGYAR RUGGYANTAARUGYAR RESZVENYTARSASAG, OF BUDAPEST, HUNGARY,
A CORPORATION OF HUNGARY

DESIGN FOR A TOY

Application filed April 14, 1933. Serial No. 47,787. Term of patent 7 years.

To all whom it may concern:

Be it known that I, LADISLAS TURCHANYI, a citizen of Hungary, residing in the village of Sashalom, near the city of Budapest, Hungary, have invented a new, original, and ornamental Design for a Toy, of which the following is a specification, reference being had to the drawing, forming a part thereof.

The drawing shows a perspective view of the front of a toy embodying my new design, the opposite side being similar and complementary thereto.

I claim:

The ornamental design for a toy substantially as shown and described.

LADISLAS TURCHANYI.
